UNITED STATES PATENT OFFICE.

JOHN W. GORDON, OF MARIETTA, OHIO.

RAILWAY-SWITCH.

SPECIFICATION forming part of Letters Patent No. 682,058, dated September 3, 1901.

Application filed April 10, 1901. Serial No. 55,160. (No model.)

To all whom it may concern:

Be it known that I, JOHN W. GORDON, a citizen of the United States, and a resident of Marietta, in the county of Washington and State 5 of Ohio, have invented a new and Improved Railway-Switch, of which the following is a full, clear, and exact description.

This invention relates to switches for street-railways and means for operating the switch 10 from a moving car on the railway-track.

The object of my invention is to provide a novel mechanism for a device of the character indicated which is practical in operation and which may be controlled from either end 15 of a car, as may be desired.

The invention consists in the novel construction and combination of parts, as is hereinafter described, and defined in the claims.

Reference is to be had to the accompanying 20 drawings, forming a part of this specification, in which similar characters of reference indicate corresponding parts in all the figures.

Figure 1 is a side view of the lower portion of a street-railway car, a railway-track, and 25 features of the improvement on the track and car engaged to operate a switch. Fig. 2 is a plan view of the main track and side track of a street-railway and of the improved switch shown connecting said tracks. Fig. 3 is an 30 enlarged transverse sectional view of the railway and of switch mechanism thereon and an end elevation of a car in part, showing details of the invention thereon. Fig. 4 is an enlarged longitudinal sectional view of the im- 35 proved switch mechanism substantially on the line 4-4 in Fig. 2; and Fig. 5 is an enlarged longitudinal sectional view of an end portion of the car, showing details of the invention thereon, the section being substantially on the 40 line 5-5 in Fig. 3.

In the drawings, 66 indicate the main-track rails, and 77 the side-track rails, connected to the main track by the improved switch mechanism, comprising the following details:

45 A preferably rectangular box 8 is embedded in the roadway between the main-track rails 6 and flush at the upper edge with said roadway and held in place by bolts inserted through ears 8^a, formed on the ends of the 50 box and screwed into tapped holes in plates or the like secured upon the cross-ties, as shown in Fig. 2. A frog 9 of the usual form

is introduced at the junction of one side-track rail 7 with an adjacent main-track rail 6, and a tongue 10 is pivoted by one end upon an 55 end of the opposite side-track rail, said tongue being tapered laterally to provide a point at the free end of the same which may impinge upon the inner surface of said main-track rail. A cover-plate 11 is hinged by one end 60 upon an appropriate end wall of the box 8, so that said plate may rock within the box, which it loosely covers, and essentially close the box at the top, as shown in Figs. 3 and 4. The cover-plate 11 is reduced in length at its 65 free end, producing a lug or flange *a* at each side, and in the space thus provided a roller 12 is journaled by pivots that loosely engage within perforations in the lugs or flanges *a*, as indicated in Fig. 2, the body of the cylindrical roller projecting a suitable degree 70 above the cover-plate, as shown in Fig. 4.

A rock-shaft 13 is held longitudinally in the box by a journaled engagement of its ends with suitable boxes *b*, positioned intermediately of the side walls of the box, as best shown in Fig. 3. A crank-arm *c* is formed or secured upon the body of the rock-shaft 13, preferably nearer the free edge of the cover-plate 11 than its hinged end. Upon the end 80 of the crank-arm *c* a roller *d* is pivoted and is designed to bear upon the lower surface of the cover-plate 11 near the transverse roller 12. A second arm *e* is projected from the rock-shaft 13 near the end wall of the box 8, upon 85 which the cover-plate 11 is hinged, and upon the free end of this arm *e* one end of a pusher-bar 14 is pivoted, the elongated body of said bar projecting loosely through an opening *g* in the end wall of the box 8, as shown in 90 Figs. 3 and 4. The pusher-bar 14 is so relatively positioned as to locate its outer end adjacent to the free end or point of the tongue 10, from which a short lug depends, whereon the outer end of the pusher-bar is 95 pivoted, as shown at *h* in Fig. 3. Upon the pusher-bar 14, outside of the box 8, a strong spiral spring 15 is mounted and secured by its end which is nearest to the tongue 10, the free end of said spring having enforced 100 contact with the outer side of the box 8 where the bar passes loosely therethrough.

The proportion of parts should be such as will adapt the spring 15 to normally press

the point of the tongue 10 against the side of the main-track rail 6 and so rock the shaft 13 as to dispose the arms *c* and *e* nearly upright, whereby the roller *d* is pressed with sufficient force against the cover-plate 11 to elevate its free end and the roller 12 a suitable distance above the top of the box 8, as shown in Fig. 4.

It will be seen that if pressure is applied upon the roller 12, so as to depress the cover-plate 11, this in turn will rock the shaft 13 and pull upon the pusher-bar 14, compress the spring 15, and remove the point of the tongue 10 from the track-rail 6, thus opening the switch for passage of cars upon the main track through the switch.

In order to limit the depression of the free end of the cover-plate 11, abutments *f* are formed on the inner sides of the box 8, whereon the plate will seat after it has been rocked downward a proper distance. To enable a depression of the cover-plate 11 to be effected reliably by an operator on the car *A* as the car approaches the switch, a novel mechanism is located upon the car and comprises the following details: Upon the under side of each of the car-platforms *A'*, near the outer end and transverse center thereof, a bracket-arm 16 is secured, each bracket-arm having a member 17 hinged thereon, so as to depend from the lower portion of the arm. Upon the rockable members 17 a presser-bar 18 is secured, which is thus held parallel with the track-rails 6, and has sufficient length to adapt said presser-bar to extend a short distance in advance of each car-platform *A'*. Near each end of the presser-bar 18 a curved lever 19 may be secured by one end, so as to project laterally and upwardly through the floor of a respective platform *A'*, each curved arm, if two are provided, having a footpiece *m* on its upper end. Preferably each curved lever 19 is pivoted upon the depending member 17 of a respective bracket-arm 16, and between the ends of the presser-bar 18 a retractile spring 20 is secured by one end thereto, the opposite end of said spring being affixed upon the lower side of the car-frame or floor of the car. It will be seen that the spring 20 normally holds the presser-bar 18 rocked laterally and upwardly, which removes it from the railway-track, and at the same time the curved lever or levers 19 are projected up through the platforms *A'* a corresponding degree.

In service as the car *A* on the main track approaches the switch and if it is desired to pass the switch for traverse of the car upon said main track the operator on the front platform applies foot-pressure upon the upper end of the curved lever 19 and forcibly depresses it. The depression of the lever 19

correspondingly moves the presser-bar 18 downward, so that the sloped end of said presser-bar will impinge upon the roller 12 65 and push it, and with it the cover-plate 11, downward, and this downward movement will pull upon the bar 14, compress the spring 15, and remove the point of the tongue 10 from the main-track rail 6, as has already 70 been explained.

It will be seen that the position given to the box 8 and rockable cover-plate 11, together with the length of the roller 12, will adapt a car having the adjustable presser-bar 18 75 thereon to depress said roller and cover-plate if the car is moving upon the main track in either direction, and thus open the switch, so that the car may pass it and continue moving on the main track. It will also be observed that the car will leave the main track and pass upon the other track if the tongue 10 is left in normal adjustment, which may be of advantage in many situations on a street-railway. 85

Having thus described my invention, I claim as new and desire to secure by Letters Patent—

1. In a device of the character described, the switch mechanism, comprising a box positioned between the main-track rails, a rockable cover-plate on said box, a roller carried by the cover-plate at its free end, a rock-shaft pivoted in the box by its ends, an arm on said shaft, a roller pivoted on the free end of said arm and adapted to contact with the cover-plate, a second arm on the rock-shaft, a pusher-bar projecting through a wall of the box and pivoted by one end on the second arm, the other end of said pusher-bar being pivoted upon a projection on the tongue near its point, and an expanding spring mounted upon the pusher-bar, and adapted to press said bar for closure of the tongue-point against the main-track rail to which it is adjacent. 95 100 105

2. In a device of the character described, the switch-adjuster carried upon a car, comprising a presser-bar held to rock longitudinally of said car, by its attachment upon pivoted depending members of two bracket-arms 110 secured near respective ends of the car, a retractile spring having its ends respectively affixed upon the presser-bar and upon the car, and a curved lever loosely connected by one end with the presser-bar, and having its upper end extended through the platform of the car to receive foot-pressure. 115

In testimony whereof I have signed my name to this specification in the presence of two subscribing witnesses.

JOHN W. GORDON.
